BUTTON-DRILLING MACHINE.

1,083,202.

Specification of Letters Patent.

Patented Dec. 30, 1913.

Application filed April 3, 1912. Serial No. 688,259.

To all whom it may concern:

Be it known that we, PAUL F. DUSHA, ANTON FEYK, and JOSEPH KOMANCSEK, citizens of the United States, residing at New York, in the county of New York and State of New York, have invented certain new and useful Improvements in Button-Drilling Machines, of which the following is a specification.

10 Our invention relates to button forming machinery, and particularly to mechanism for drilling button eyes.

15 The primary object of our invention is the provision of means whereby a plurality of eyes may be drilled simultaneously through a button.

20 A further object is to provide a button forming machine having a button engaging chuck laterally shiftable and longitudinally movable to feed the button against the cutting and drilling mechanism, in combination with a laterally shiftable cutting wheel and a fixed head carrying a plurality of eye-forming drills.

25 A further object is the provision of means whereby a plurality of drills may be so supported that the cutting ends of the drills are disposed all within a relatively small area, while the rear ends of the drills are supported at such distance from each other as to provide for the accommodation of driving mechanism, and also provide for proper and ready adjustment of the drill, drill chucks, bearings, etc.

30 Another object is the provision of means for adjustably clamping the drills in place, each in its respective chuck.

35 A further object is the provision of means whereby all or any one of the drills and drill chucks may be withdrawn from the head within which they are supported.

40 Another object is to provide means for adjusting the thrust bearings of the several drills, and further to provide means in this connection for gaging the alignment of the several drills so that the cutting extremities of the drills may be quickly brought into coincidence with the same plane.

45 Other objects will appear in the course of the following description.

Our invention is illustrated in the accompanying drawings wherein:

50 Figure 1 is a side elevation of a button boring and cutting machine constructed in accordance with our invention. Fig. 2 is a

longitudinal section of the drill supporting head and the chucks therefor, the drills being shown in operative position. Fig. 3 is a longitudinal sectional view of the several parts constituting one drill chuck, the parts being separated from each other, a fragment of the sleeve 23 being also shown. Fig. 4 is a transverse sectional view on the line 4—4 of Fig. 2. Fig. 5 is a top plan view of the drill supporting head, the extension thereof and the drill supported therein. Fig. 6 is a sectional view of the internal gear and pulley, the rear cap, the disk 24, the thimble 33, the guide 60 and the guide 57.

Corresponding and like parts are referred to in the following description and indicated in all the views of the accompanying drawings by the same reference characters.

In the drawings, 2 designates a base plate of any suitable construction upon which at 75 one end is mounted a vertically and laterally adjustable button chuck support comprising in the instance described a longitudinally movable base 3 having a keyway receiving a key 4 on the base plate 2.

80 The upper face of the member 3 is provided with a laterally extending dovetailed tongue 5 engaging with a section 6 having a dovetailed slot in its under side receiving the tongue. Vertically adjustable on the member 6 is a pillar 7 having journal boxes in which are supported a button chuck provided with button engaging jaws 9. This button chuck is vertically adjustable by means of the adjusting screw 8 provided with a perforated head at its middle whereby it may be operated.

85 Mounted on the base plate 2 in front of the button chuck supporting member is a pillar 10 upon which is mounted a laterally shiftable slide 11 carrying a button cutting disk or wheel 12 which may be used either for knurling the margin of the button, facing it, or for cutting a "fish-eye" therein. As illustrated, the slide 11 has a dovetailed 90 groove engaging a dovetailed tongue 13 projecting up from the pillar 10.

95 All the parts heretofore described are of a well known form and hence need no extended description, nor is it believed to be necessary to show or describe the means whereby the button engaging chuck may be operated, or the means whereby the wheel 12 may be driven.

100 Our invention lies in combining with the

parts above referred to a fixed drill supporting head and in so forming the head as to provide for attaining the objects referred to in the first part of this specification. As illustrated in Fig. 2, this drill chuck supporting head consists of a substantially cylindrical shell designated 14 supported by a pillar 15 mounted upon the base plate 2 as will be later stated. This shell 14 is formed in two sections spaced from each other, the forward section being designated 14^a and the rear section 14^b. These sections are non-rotatable and rigidly mounted upon or formed with the post 15, the latter being cut away at 15^a between the sections of the shell. The rear end of the shell 14, and specifically the rear end of section 14^b is closed by a circular cap 16 having an annular seat 17 formed in its inner face to receive the rear end of section 14^b of the head. Screws 18 pass through the margin of the cap into the section 14^b, the heads of the screws being received in recesses formed in the outer face of the cap.

The central portion of the cap is bulged outward on its outer face and recessed in its inner face as at 19, and the cap is formed with a plurality of screw threaded openings 20 for the reception of adjusting nuts to be later described.

30 The forward end of the forward section 14^a is contracted as at 21, and extending therefrom and preferably forming part thereof, is a semi-tubular prolongation 22 for a purpose to be later stated.

35 Mounted within the head 14 and rotatable therein is a sleeve 23 which at its forward end abuts against the inner face of the contracted portion 21, the rear end of this sleeve 23 bearing against a disk or bushing 24 having perforations 25 therein for the passage of the drill chucks. The inner face of the sleeve 23 near its rear end is outwardly beveled as at 26 and formed with gear teeth 27. The sleeve 23 therefore forms an internal 45 driving gear for the drill chucks.

Mounted on the sleeve is a pulley 28 which is disposed in the space between the forward and rear head sections 14^a, 14^b and which as illustrated is held in rigid engagement with the sleeve by a set screw 29. This pulley is driven by means of a belt 30. We do not of course wish to be limited to the use of a belt, nor to the use of a pulley as a means for driving the gear sleeve 23, it being obvious that other means might be provided for this purpose without departing from the spirit of the invention.

Disposed on each side of the pulley 28 and surrounding the projecting ends of sleeve 23 are the bushings 31 and 32. These bushings have their forward and rear ends respectively abutting against the forward and rear ends of the sleeve 23 as illustrated in Fig. 2. The disk 24 abuts against the rear ends of

sleeve 23 and bushing 32, while the forward ends of sleeve 23 and bushing 31 bear against the inside face of the contracted end 21 of the head 14.

Disposed within the contracted end 21 of shell 14 is a collar or thimble 33 having a flange 34 at its rear end and formed with a plurality of perforations 35 for the drill chucks. It is to be particularly noted at this point that the cap 16, disk or bushing 24 and the collar or thimble 33 are all provided with the same number of perforations arranged in the same relation, and that the axis of each of these perforations is at an inclination to the axis of the head 14 so that each perforation extends forward and toward the axial center of the sleeve 23, and that the corresponding perforations in the three supporting members 16, 24 and 33 are in alignment, a line extending through the axes of all the corresponding perforations 35 of the disk 24, the collar 33 and the cap 16 being inclined to the axis of the head and extending forward and centrally with relation to said axis. It is also to be noted that the gear teeth 27 are inclined toward the front and center of the head 14. Disposed within the sleeve 23 are a plurality of drill chucks designated 36 and illustrated in Fig. 3. Each chuck is tubular and has a uniform bore extending from end to end. The forward end of this tubular member of the chuck is formed with an inwardly projecting annular flange 37 having a forwardly and centrally beveled or inclined inner face.

The rear end of the tubular member is enlarged as at 38 to form a head recessed at 39 at its rear end, that portion of the bore within the head being screw threaded as at 40. The middle of each tubular chuck member is provided with gear teeth 41. These teeth are inclined forwardly and centrally so as to mesh with the gear teeth 27. The head 38 fits snugly in the corresponding perforation 25 in the ring or disk 24 while the forward end of the tubular member which is slightly enlarged in diameter fits snugly within the corresponding perforation 35 in the collar 33. It will be noted that each perforation 35 is slightly tapered. The enlarged end 36 of the tubular member is also slightly tapered so that while the tubular member 36 may be withdrawn rearwardly from the collar 33, it will seat when forced home to the position shown in Fig. 2.

Disposed within the bore of each tubular member 36 is a tubular drill gripping member 42, made in two sections, the forward section having a uniform exterior diameter for a portion of its length, and at its forward end split or slotted as at 43 to form a plurality of resilient jaws 44, the jaws at the forward ends contacting with each other as at 45, and being formed with

beveled ends 46 which coat with the internally beveled flange 37 on the tubular member.

At its rear end the rear section of the gripping member 42 is formed with a polygonal head 47 whereby a wrench may be applied to rotate the drill gripping member within the tubular member of the chuck. Forward of this head the member 42 is cylindrical in form as at 48, and forward of this in turn the member 42 is screw threaded as at 49, these screw threads engaging with the internal screw threads 40 on the tubular member 36 as clearly shown in Fig. 2.

Disposed within the recess 39 of each of the tubular members 36 is a bearing sleeve or bushing designated 50 (see Fig. 3). This bearing sleeve or bushing has the same internal diameter as the external diameter of the portion 48 of the tubular member 42, and the same external diameter as the internal diameter of the recess 39. Surrounding the extremity of the portion 48 rearward of the bushing 50 is a thrust nut 51 illustrated in Fig. 3. This thrust nut as shown in the sectional view, Fig. 2, has an internal diameter equal to the external diameter of the portion 48 of the tubular member 42 and is provided with a polygonal head 52 and a screw threaded portion 53 which is adapted to engage with the internal screw threaded perforations 20 in the cap 16. The head 47 of the tubular member 42 of course projects through this bushing 51 as illustrated in Fig. 2 so that a wrench may be applied either to the head 47 or to the head 52 as desired. This member 51 bears against the sleeve 50, and by screwing inward on the member 51, the bushing or sleeve 50 may be forced forward to bear with more force against the tubular member 36, thus forcing this tubular member to its seat in the collar or bushing 33. By rotating the nut 51 in a reverse direction, the pressure upon the tubular member may be decreased. For the purpose of holding the nut 51 in any adjusted position, a lock nut 54 is applied to the exterior thereof as illustrated in Fig. 2, which lock nut bears against the end of the cap 16.

Supported within each of the tubular drill clamping members 42 is a drill illustrated in Fig. 3 and designated 55. This drill may be of any suitable length and of any suitable character. The drills used on this machine are ordinarily very small in diameter and relatively long so that they project out a considerable distance beyond the extremities of the jaws 45.

The forward end of the semitubular prolongation 22 of the head 14 is formed with a collar 56 upon which is mounted a cap 57 perforated at a plurality of points for the passage of the cutting extremities of

the drills 55. This cap 57 has an internal flange 58 which extends into the bore of the collar 56. This cap 57 is held in place by means of a set screw 59 passing through the collar 56. This cap 57 constitutes a guide for the extremities of the drills. It will be noted that the drills are all inclined forward and toward a common center, and that therefore they would bore perforations through the button which would also be inclined from the front to the rear of the button and toward a common center. For the purpose of preventing this and bending the flexible drills so that the extremities of the drills shall be parallel with each other, we have provided this cap or guide 57 and form the cap or guide with parallel perforations through which the drills pass. These parallel perforations tend to bend the drills to a very slight degree from an angular relation to each other into a parallel relation.

In order to support the projecting ends of the drill and prevent any flexing of the drills, we provide a shiftable disk 60 which is perforated for the passage of the several drills, these perforations being inclined forwardly and centrally with relation to the axis of the disk 60.

The shell forming the prolongation 22 is longitudinally slotted as at 61 and the disk 60 is attached to a plate 62 adjustably disposed upon the exterior of the prolongation 22, this disk passing through the slot 61. The plate 62 is longitudinally slotted as at 63 and engages with a fixed binding screw 64 which is mounted upon the wall of the prolongation 22 and extends out through the slot 63 and is provided with a nut 65. It will be seen that this construction permits the disk 60 to be adjusted longitudinally so as to secure a proper bearing and support for the drills 55.

For the purpose of gaging the drills 55 so as to bring their cutting ends all into one plane, we provide the slidable gage 66 which is mounted in a barrel 67 formed upon the extension 22. This gage consists of a rod which passes through the barrel 67 and which at its extremity is angularly bent as at 68, this angularly bent end carrying a flattened terminal portion 69 which is adapted to be placed immediately in front of the openings through the guide 57 so that the drills may be shifted until their extremities come in contact with the flattened terminal end 69. When the drills are thus adjusted so that their extremities are all in one plane, the guide is then turned up as shown in dotted lines in Fig. 2. The guide bar 66 is provided with a stop 70 preventing the withdrawal of the guide beyond a certain point and gaging the distance of the terminal end 69 with relation to the face of the guide 57.

While we do not wish to be limited to any

particular means for mounting the drill head, we have shown as before stated, the tubular portion 14 as being mounted upon a post 15. As illustrated in Fig. 2, this post is formed with a central cylindrical depending portion 71 supported within a socket-like sleeve 71^a having an outwardly projecting flange 72 at its upper margin. This socket-like member 71^a rests within the hole 19 low upper end of a base 73 which is provided at one side with a projecting lug 74 having a screw threaded passage passing therethrough. The member 71 is also provided with an outwardly projecting screw threaded lug 75, and passing through both of these lugs is a screw 76 formed with a median head 77 disposed between the lugs 74 and 75 and whereby the socket member 71 with the post 15 may be raised or lowered 20 and thus the drill head adjusted vertically. After its adjustment, the drill head may be held in any desired permanently adjusted position by means of a set screw 78 provided with a handle 79.

25. The operation of our invention is as follows: The drills having been adjusted, and a button placed within the button chuck 9, power is applied to the internal gear 23 by the pulley 28. As the internal gear rotates 30 in one direction, it will rotate the several drill chucks, and as the button is moved forward against the extremities of the drills, the button will be perforated. At any time the bearings for any one of the several drill 35 chucks may be adjusted by rotating the nuts 53. When these nuts are rotated inward, they bear against the collar or bushing 50, and this in turn bears against the head 38 of the drill chuck 36, forcing the chuck forward 40 more firmly into the seat formed in the collar 33. By engaging the head 47 of the chuck member 42, the jaws may be tightened or loosened upon the drill, the jaws being loosened to permit the drill to be adjusted within the jaws and tightened after 45 the drill is adjusted. It will be obvious that by removing the nut 53, the bearing collar 50 may be removed or replaced, and that the entire chuck may be withdrawn 50 from the rear end of the machine, the bushing 24 holding the internal gear 23 and the bushings 31 and 32 in place. By removing the cap 16, it is possible to remove the bushings 24 and 32, the sleeve 23 and the thimble 55 33 so that the parts may be repaired or replaced.

What we claim is:

1. In a button perforating machine, a drill head, a plurality of drill chucks carried in the head, each chuck being independently adjustable longitudinally with relation to the head and removable through the rear end of the head, and removable means for holding the chucks in place within 65 the head.

2. In a button perforating machine, a fixed drill head, a plurality of drill chucks disposed within the head, bearings disposed within the head within which said drill chucks revolve, common means for rotating the drill chucks, and means disposed at the rear end of the head for holding the chucks in place within the head, said means being removable to permit the removal of the chucks through the rear end of the head. 75

3. In a button perforating machine, a fixed drill head, a drill chuck extending longitudinally through the head, means for rotating said drill chuck, bearings in the head within which said drill chuck is mounted for rotation, said bearings converging toward the forward end of the head to form seats for the chuck, and means for adjusting said chuck into or out of said bearings. 80

4. In a button perforating machine, a fixed head, a plurality of drill chucks carried in the head, a plurality of bearings mounted in the head through which said chucks pass, said bearings having conical faces to form seats for the chucks, and removable bushings disposed within the rear end of the head and engaging said chucks, said bushings being adjustable to force the chucks toward the front of the head and into more or less engagement with the seats therefor or removable to permit the removal of any one chuck independent of the others. 95

5. In a button perforating machine, a button chuck, a drill head, a plurality of drill chucks carried in the head, means disposed within the head for rotating said chucks, said chucks being directed toward the button chuck and toward a common center, a shiftable guide through which the drills pass, and a fixed guide disposed in 100 advance of the shiftable guide and having drill passages extending parallel with each other.

6. In a button perforating machine, a button chuck, a hollow drill head, an internal gear mounted within the drill head, a plurality of bushings mounted within the drill head and formed each with drill chuck passages converging toward the forward end of the head, and a plurality of drill chucks 115 converging toward the forward end and supported in the passages in said bushings, each chuck being formed with a pinion engaging the internal gear.

7. In a button perforating machine, a 120 hollow drill head, an internal gear supported therein, a cap closing the end of the drill head and having a series of screw threaded passages through it, a plurality of bushings disposed within the drill head and having a 125 series of chuck-receiving passages therethrough, a plurality of drill chucks mounted in the passages in said bushings and converging toward the forward end of the machine and nuts, one for each of said chucks 130.

operatively bearing against the extremity of the chuck and engaging the screw threaded passages in the cap.

8. In a drilling machine of the character described, a head, a drill chuck supported therein and interiorly screw threaded for a portion of its length, a drill gripping member disposed within the chuck and exteriorly screw threaded for a portion of its length to engage with the exterior chuck member, said interior member being provided with drill gripping jaws and with a polygonal shank projecting beyond the chuck, and a drill passing longitudinally through the interior member and engaged by said jaws.

9. In a button perforating machine, a hollow drill head, an internal gear supported therein, means for driving said gear, a cap disposed at the rear end of the drill head and having a plurality of screw threaded passages, a disk-like member disposed within the head and having a plurality of tapered passages corresponding in position to the position of the passages in the cap, a plurality of drill chucks operatively engaged by the internal gear, thrust nuts engaging the passages in the cap operatively engaging the chucks to force them to seat within the tapered passages of the disk like member, and drill gripping members disposed within the chucks extending rearward beyond the said nuts and having a screw threaded engagement with the chucks whereby the gripping members may be closed upon the drill as they are forced into the chucks.

10. In a button perforating machine, a drill head, chuck bearings supported within the drill head, a plurality of chucks supported in said bearings, means for adjusting the chucks longitudinally relative to the drill head, drill clamping members disposed within the chucks, the chucks having means for causing said members to grip a drill upon the inward movement of the drill gripping members, and means for longitudinally shifting the drill gripping members with relation to the chucks.

11. In a button perforating machine, a drill head, chuck bearings mounted within the drill head, a plurality of chucks supported in said bearings, means for adjusting the chucks longitudinally relative to the bearings and head, means for rotating the chucks, drill engaging members including drill gripping jaws, and means for adjusting said drill engaging members longitudinally to clamp said jaws upon a drill.

12. In a button perforating machine, a drill head, a plurality of rotatable chucks, each chuck having an inwardly turned annular flange at its forward extremity, the inner face of said flange being tapered, means disposed within the head for rotating said chucks, bearings within the head for supporting the chucks, means for longitudi-

nally adjusting the chucks relative to the bearings, drill gripping members disposed, one within each of the chucks and including drill gripping jaws having inclined forward ends adapted to engage with the inclined flanges on the forward ends of the chucks whereby to cause an inward movement of the jaws upon a forward movement of the gripping members, and means for adjusting said gripping members longitudinally within the chucks whereby to cause the closing of the jaws upon a drill.

13. In a button perforating machine, a hollow fixed drill head formed in two longitudinally spaced sections, an internal gear disposed within said sections, a pulley attached to said internal gear and projecting out between said sections, a plurality of non-rotatable chuck supporting members disposed within said head and having corresponding chuck-receiving passages, a plurality of independently rotatable chucks disposed within the passages of said supporting members and having gear teeth engaging said internal gear, and drill gripping devices mounted in said chucks.

14. In a button perforating machine, a hollow drill head formed with spaced sections, an internal gear mounted within said drill head, a pulley on the internal gear projecting out between said sections, a cap closing the rear end of the head and formed with a plurality of screw threaded chuck-receiving passages, a plurality of chuck-supporting members carried by said head and formed, each with a plurality of chuck-receiving passages corresponding in position to the position of the chuck-receiving passages of the head, a plurality of chucks disposed in said passages and longitudinally movable with relation to the head, a plurality of thrust nuts disposed in the screw threaded passages of the cap and operatively engaging the rear ends of the chucks whereby to adjust said chucks longitudinally, and a plurality of drill gripping members, mounted, one in each chuck and having drill engaging jaws, said members being independently longitudinally movable to adjust said jaws upon a drill.

15. The combination with a plurality of drill chucks and longitudinally adjustable drills carried thereby, of a gage movable into or out of position in front of the cutting points of said drills whereby the drills may be adjusted to bring their cutting points in the same plane.

16. The combination with a drill head, an extension projecting from the forward end thereof and a plurality of drill chucks supported in said head, of a gage mounted upon the forward end of said extension longitudinally and rotatably movable to adjust the gage into position in front of the points of the drills or out of such position.

17. In a button perforating machine, a base, a hollow drill head supported on the base and having an extension therefrom, a plurality of chucks supported in the base, means for rotating said chucks, drill-gripping devices coacting with said chucks, said chucks converging toward the front end of the drill head, a disk-like member mounted in said extension and longitudinally shiftable with relation thereto and having a plurality of forwardly converging perforations through which the drills supported in said chucks are adapted to pass, and a member carried by the forward end of said extension and having a plurality of perforations, one for each of the drills.

18. In a button perforating machine, a base, a plurality of chucks supported on the base, said chucks converging toward the front end of the drill head, means for rotating the chucks, drill gripping devices coacting with the chucks, and a member operatively supported in front of the chucks and longitudinally shiftable with relation thereto and having a plurality of forwardly converging perforations through which the

drills supported in said chucks are adapted to pass.

19. In a button perforating machine, a base, a plurality of chucks supported on the base, said chucks converging toward the front end of the drill head, means for rotating the chucks, drill gripping devices coacting with the chucks, a member operatively supported in front of the chucks and longitudinally shiftable with relation thereto and having a plurality of forwardly converging perforations through which the drills supported in said chucks are adapted to pass, and a member carried by the forward end of said extension disposed in front of the last named member and having a plurality of perforations one for each of the drills.

In testimony whereof we affix our signatures in presence of two witnesses.
